(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment;

FIG. 3 is a front view of a display screen or portion thereof with graphical user interface showing our new design according to a third embodiment;

FIG. 4 is an enlarged view of a portion of the graphical user interface of FIG. 1, shown separately for clarity of illustration;

FIG. 5 is an enlarged view of a portion of the graphical user interface of FIG. 2, shown separately for clarity of illustration; and,

FIG. 6 is an enlarged view of a portion of the graphical user interface of FIG. 3, shown separately for clarity of illustration.

The outer perimeter illustrated by a pair of broken lines in FIGS. 1-3 represents a display screen or portion thereof and forms no part of the claimed design. The remaining broken lines in FIGS. 1-3 illustrate portions of the graphical user interface that form no part of the claimed design.

1 Claim, 6 Drawing Sheets
